[57] CLAIM

The ornamental design for a junction housing for battery jumper cables, substantially as shown and described.

DESCRIPTION

FIG. 1 is a pictorial view of a junction housing for battery jumper cables showing my new design, the cables and terminal clamps being shown in broken lines for illustrative purposes only;

FIG. 2 is a top view thereof;

FIG. 3 is a side view thereof, the opposite side being identical;

FIG. 4 is a bottom view thereof; and

FIG. 5 is an end view thereof, the opposite end being identical.
